UNITED STATES PATENT OFFICE.

WILLIAM BRIDGEWATER, OF DONCASTER, ENGLAND.

BOXING GLOVE.

Application filed November 27, 1923. Serial No. 677,308.

To all whom it may concern:

Be it known that I, WILLIAM BRIDGEWATER, a subject of the King of England, residing at Doncaster, England, have invented 5 certain new and useful Improvements in and Relating to Boxing Gloves, of which the following is a specification, reference being had therein to the accompanying drawing.

10 This invention relates to boxing gloves.

The invention has for its object to provide boxing gloves of such improved design and construction that better protection for the hands of the wearer is provided, injury to 15 the thumbs and illegal use of the latter are positively prevented, and objectionable holding or clinching tactics are greatly minimized.

According to the invention the gloves are 20 constructed thumbless, that is without projecting or separate thumb stalls or thumb coverings, the thumb stall or thumb covering of each glove being an integral part of the whole glove, in distinct contrast to the 25 old type of glove which allowed the projecting thumb stall to be extended or outstretched at will.

The invention will now be described with 30 reference to the accompanying drawings, in which:—

Figure 1 is a perspective view illustrating a suitable manner of carrying out the invention,

Figure 2 is a perspective view showing a 35 modification, and

Figure 3 is a side view of the glove shown in Figure 2.

Thus in a suitable manner of carrying out the invention the glove may be so constructed 40 that the whole of the hand, including the thumb, is adapted to be enclosed within a single case or stall *a*, Figure 1, the leather or other outer covering of which is formed primarily in one piece or of any 45 suitable number of pieces sewn or otherwise fastened to one another. The interior of the glove may be so constructed that the thumb is, comparatively speaking, free 50 therein, or said interior may be provided with a pocket or stall adapted to receive the thumb whilst allowing sufficient movement of the latter inside the glove to permit of 55 obtaining an adequate closing and clinching of the hand as a whole and a proper grip on the glove.

In a modified construction of the glove

the same may comprise a main stall, case or section *a'* Figures 2 and 3, for receiving the fingers and the palm of the hand, and a secondary stall, case or section *b* to accommodate or protect the thumb, the two stalls, cases or sections being formed integrally with one another in any suitable manner, that is, the thumb stall is united to the body of the glove throughout the entire length of 60 such thumb stall. This construction of the glove would give to the latter the outward appearance of being provided with a separate stall for the thumb, whilst at the same time providing for the requisite freedom of 65 movement of the fingers and thumb in extending and clinching the hand and in obtaining a tight grip on the glove, and facilitating the manufacture of the glove as regards the location of the padding and the 70 fastening together of its various parts. In this construction also the thumb may be free within the glove or be arranged within an interior pocket.

According to another modification, not 75 shown, the glove may be made the same as or similarly to the gloves now in common use and having a separate thumb stall, in which case said stall would be fastened down on to the main or body portion of the 80 glove either permanent or temporarily and by sewing or in any other convenient manner, thus retaining the feature of the invention of providing a boxing glove having no 85 projecting thumb stall.

In any of the constructions above described the interior of the glove may be provided with pockets or stalls to receive the fingers; the amount and distribution of the padding within the glove may be varied; 90 preferably, the part *c* of the glove disposed adjacent to the outer side of the hand is well padded to prevent the inflicting of illegal blows on an opponent by chopping tactics; the grip upon the glove and the strength of 95 the latter as a whole may be increased by providing one or more leather bars or ribs *d* extending across the inside of the glove; these and all other details of construction and manufacture of the gloves would depend upon the class and selling price of the 100 latter and upon any other special requirements.

What I claim is:—

110 1. A boxing glove having a main stall to receive the fingers and palm of the hand, and a secondary and externally arranged

stall to accommodate the thumb, the secondary stall being secured throughout its length to the main stall.

2. A boxing glove having independent finger and thumb stalls integrally connected throughout their length, the thumb stall appearing externally of the glove, the integral

connection of the stalls preventing the thumb from being extended independently of the rest of the hand. 10

In testimony whereof I have hereunto signed my name.

WILLIAM BRIDGEWATER.
